UNITED STATES PATENT OFFICE.

HARRY A. FOOTHORAP, OF HARRISBURG, PENNSYLVANIA, ASSIGNOR TO ELLIOTT-FISHER COMPANY, A CORPORATION OF DELAWARE.

TYPE ACTION FOR TYPEWRITERS.

Application filed April 30, 1923. Serial No. 635,677.

To all whom it may concern:

Be it known that HARRY A. FOOTHORAP, a citizen of the United States, residing at Harrisburg, in the county of Dauphin and State of Pennsylvania, has invented certain new and useful Improvements in Type Actions for Typewriters, of which the following is a specification, reference being had therein to the accompanying drawing.

10 This invention relates to an improved type action for typewriting machines, and more particularly, to an action of the down strike type ordinarily employed in what are known as flat platen typewriters.

15 The object of the invention is to produce an action which, while being characterized by extreme simplicity of construction and economy of manufacture will nevertheless embody the essentials of light touch, accelerated printing movement, and locking 70 of the type bar in normal position.

20 To the accomplishment of this object, the invention resides in the construction and relation of parts to be hereinafter described, 25 illustrated in the accompanying drawings and defined in the appended claims.

In said drawings,

25 Figs. 1, 2, 3 and 4 are side elevations of the action with the parts shown in progressive positions.

30 A horizontally disposed key lever 1 having the usual key 2 at its front end is fulcrumed at its rear end 3 and provided intermediate of its ends with the usual guide 4. Below the key lever the type bar 5 is mounted to swing from its lower end in the type ring 6 and has mounted at its opposite end the usual type 7. Normally the type bar 5 stands in a vertical position as 35 shown in Fig. 1 and rests against a buffer ring 8. The hub 9 of the type bar 5 has the usual short arm or projection 10 disposed below and in the rear of the type bar pivot 11 and is connected to the lower 40 end of a draw wire 12, the upper end of which is connected to the end of the long arm 13 of a sub-lever 14 fulcrumed at 45 15 in a plane above the key lever and forward of the fulcrum thereof.

50 The normal relation of the connection 13^a between the wire 12 and the lever 14 is slightly back of a line drawn through the lever fulcrum 15 and the connection 10 between the draw wire and the type arm, to 55 effect the locking of the type arm against

rebound after it has been retracted. It will be seen that any tendency of the bar to rebound will be resisted by the fulcrum 15 of the lever 14 because the connections between said fulcrum and the type bar connection 10 are substantially in line with, though slightly in rear of said fulcrum.

55 The short arm 16 of the cam lever 14 is formed with a cam slot 17 in which is arranged to play a roller pin 18 carried by 65 the key lever 1. The configuration of the slot 17 is such that the maximum leverage will be exerted at the first part of the printing stroke to overcome the inertia of the parts, this leverage being gradually decreased and the movement accelerated as 70 the type bar proceeds on its excursion to the platen.

75 A convenient mounting for the key lever is in the form of a horizontal deck 19 carrying the guide 4 in the form of a comb plate and having key lever bearing lugs 20, and cam lever bearing lugs 21 dropped below the deck.

80 Forced alignment is secured by an alignment guide 22 which receives the type bar adjacent to the free end thereof as the type reaches the printing point.

85 Of course, the action is provided with one or more retracting springs applied to the key lever or other part of the action.

90 It is thought that from the foregoing, the construction, arrangement and advantages of my type action will be apparent but I reserve the right to effect such variations of 95 the illustrated structure as may fall within the scope of the claims.

What I claim is:

1. In a type action, the combination with 95 a horizontally disposed key lever fulcrumed at its rear end, and a normally vertical type bar mounted below the key lever, of a sub-lever connected to the type arm, and the slot and pin connection between the sub-lever and the key lever.

100 2. In a type action, the combination with a horizontal deck, a key lever and a sub-lever fulcrumed thereon, of a type bar fulcrumed below the key lever and intermediate of the ends thereof, connections between the type 105 bar and the sub-lever, said connections being normally disposed to lock the type bar against rebound, and said sub-lever having a cam slot and a pin carried by the key lever and engaging said slot, the contour of 110

the cam slot in the sub-lever and its relation to the fulcrum of said lever and to the connection with the type bar being such that the movement of the type bar will be 5 accelerated during the movement of the key lever.

3. In a type action, the combination with a key lever and a type-bar normally disposed substantially at right angles to each 10 other, of a sub-lever connected to the type-bar, and a slot and pin connection between the sub-lever and the key lever, the relation of said connection with the fulcrum of the key lever and with the connection of 15 the type bar with the sub-lever being such that the movement of the type-bar will be accelerated during the movement of the key lever.

4. In a type action, the combination with 20 a key lever and a type-bar normally disposed in substantially right angular relation, of a sublever, connections between the type bar and the sub-lever, said connections being normally disposed to lock the type-bar 25 against rebound, and a slot and pin con-

nection between the key lever and the sub-lever. The relation of said slot and pin connection to the fulcrum of the sub-lever and the key lever being such that the movement of the type will be accelerated during 30 the movement of the key lever.

5. In a type action, the combination with a horizontal deck, a key lever and a sub-lever fulcrumed thereon, of a type-bar fulcrumed below the key lever and intermediate 35 of the ends thereof, connections between the type-bar and the sub-lever, said connections being normally disposed to lock the type-bar against rebound, and a slot and pin connection between the key lever and the 40 sub-lever, the contour of the slot and its relation to the fulcrum of the sub-lever, and to the connection to the type-bar being such that the movement of the type-bar will be accelerated during the movement of the key 45 lever.

In testimony whereof I hereunto affix my signature.

HARRY A. FOOTHORAP.
